J. E. McNARY.
PACK CARRIER FOR SHELLS AND PROJECTORS.
APPLICATION FILED NOV. 14, 1918.

1,380,994.

Patented June 7, 1921.

UNITED STATES PATENT OFFICE.

JAMES E. McNARY, OF THE UNITED STATES ARMY.

PACK-CARRIER FOR SHELLS AND PROJECTORS.

1,380,994.

Specification of Letters Patent. Patented June 7, 1921.

Application filed November 14, 1918. Serial No. 262,624.

(FILED UNDER THE ACT OF MARCH 3, 1883, 22 STAT. L., 625.)

To all whom it may concern:

Be it known that I, JAMES E. McNARY, major in the United States Army, a citizen of the United States, stationed in France 5 with the American Expeditionary Forces, have invented an Improvement in Pack-Carriers for Shells and Projectors, of which the following is a specification.

The invention described herein may be 10 used by the Government or any of its officers or employees in prosecution of work for the Government, or by any other person in the United States, without payment of any royalty thereon.

15 The object of the present invention is the production of a pack carrier adapted to transport shells of such weight that two constitute a load for the ordinary pack animal.

20 The invention therefore consists in the structure of parts and in their combination for the specified purpose, substantially as herein set forth and claimed.

In the drawings which form a part of 25 this specification, Figure 1 is an end view of an embodiment of the invention wherein the carrier partakes of the pannier type; Fig. 2 is a side view thereof; Fig. 3 is a plan of the connecting link between panniers; and Figs. 4 and 5 are plan and partially sectionized edge views of one of the pad cushions.

The back-pad for supporting the carrier is indicated by 6. It consists of layers of 35 canvas and leather quilted together. The back-pad is held to the pack animal by the usual girth. Two shells constituting the load are indicated at 7 and 8.

Each pannier consists of two side bars 40 9 joined together at their lower ends by blocks 10 and at their upper ends by blocks 11. These blocks are prismatic save at their ends which are reduced to rectangular cross-section for attachment by bolts 12 to the side bars 9. Cushioning pads 13 are secured to the under surfaces of blocks 10 and 11 respectively and upon the oblique outer faces of said blocks is attached the plank 14 which forms the main wall of the 45 pannier. Along each side of this plank chocks 15 are attached and across the lower end of said plank abutting said chocks is bolted the bracket 16 forming the bottom 50

support of the pannier. Angle plates 17, bolted to side bars 9, have lag screws 18 55 passed through them into said chocks. Straps 19 provided with buckles 20 are secured to the plank 14 and to the chocks 15 whereby the shells are held in place. A channel is cut in the oblique face of block 60 11 to take the upper strap 19.

The panniers thus formed are hinged on pintles 21 to a connecting link which is arched to span the back of the pack animal. This connecting link (Fig. 3) consists of 65 two arched bars 22 hinged at their ends to said pintles and joined by prismatic sticks 23 upon which is supported a fuse box 24. The panniers thus connected are confined to the back-pad 6 by straps 25 attached to 70 the lower faces of blocks 10 and passed through buckles 26 attached to the back-pad.

An effective form of cushion for the blocks 10 and 11 is represented in Figs. 4 75 and 5. It consists of a sole-leather base 27 screwed to its respective block and a pouch formed of a band 28 connected by an internal seam with the cushion head 29. The pouch so formed is stuffed with salvage fabric and stitched to the projecting edge of 80 the base 27.

Claims:—

1. A shell carrier of the pannier type having an arched dorsal link, a pannier hinged to either side of the said link and provided with base and lateral supports for a shell, a back-pad, and straps and buckles for attaching the combined panniers to the back-pad, each pannier being provided with cushioned crossbars for supporting it upon the back-pad. 85

2. A shell carrier of the pannier type having an arched dorsal link, a pannier hinged to either side of the said link and provided 95 with base and lateral supports for a shell, a back-pad, and straps and buckles for attaching the combined panniers to the back-pad, each pannier consisting of side bars, wooden crossbars, a main wall of wood attached to the crossbars, chocks at the sides of said main wall, a bracket at the lower end of the main wall and straps provided with buckles and embracing the main wall and chocks for retaining a shell in place. 100

JAMES E. McNARY.
